Philips Company, Inc., New York, N.Y., a corporation
of Delaware

Filed Apr. 22, 1959, Ser. No. 808,183

Claims priority, application Netherlands May 19, 1958

6 Claims. (Cl. 62—37)

The present invention relates to gas-fractionating columns of the type comprising a boiler and a connection for a thermal sink, for example a gas-refrigerator, adapted to carry off vapor from the column and to condense it, provision being made of a conduit for returning condensed liquid to the column, which conduit is connected to a vapor-bubble pump causing the condensate to rise in the column. The vapor-bubble pump is in heat-conductive relationship with a body of heat-conductive material, part of which is adapted to assume a temperature higher than that of the condensate, which body is in heat-exchanging contact with a location where heat is exchanged outside the boiler and where a temperature prevails which exceeds that inside the boiler. The said body is arranged to come into heat-exchanging contact with the liquid in the boiler at a point of said body between the last-mentioned location and the vapor-bubble pump.

In this construction, the body of heat-conductive material is a copper rod which extends from the vapor-bubble pump through a vessel constituting an overflow of the boiler to a location where the temperature is considerably higher than inside the boiler.

The present invention has for its object to improve this type of gas-fractionating column so as to obtain, dependent upon the level inside the boiler, a satisfactorily damped control of the supply of reflux, that is a part of the condensate returned by the thermal sink to the column.

A rise of the liquid level inside the boiler should involve a decrease of the quantity of condensate returned to the column, while a drop of the level should involve an increase of this quantity of condensate.

It has been found that for a satisfactory control, the thermal resistance of the control member should not be too low, when oscillation is to be avoided during control.

In accordance with the invention in order to bring the body into contact with the liquid inside the boiler, provision is made for a control member connected to said body, which control member may extend into the liquid inside the boiler and is so shaped and proportioned that the thermal resistance of the member varies at different values of the spacing distance between the junction of the member with the heat-conductive member and the liquid level inside the boiler.

The control member should be so shaped that the slope of the control is substantially the same at any level inside the boiler, which means that upon corresponding changes in liquid level there follows the same change in the amount of reflux delivered by the bubble pump independent of the height of the liquid on which changes occur.

In an advantageous form of the invention, this condition is fulfilled by the use of a substantially conical pin.

In one form of the invention, the member having a part of decreasing cross-section adjoins a lead-through member passing through the boiler wall. This lead-through member consists of thermally insulating material, for example high alloy steel having a low heat conductivity, thus reducing thermal losses at the lead-through.

In a further form of the invention, the control member is housed in a receptacle surrounding the member for the greater part and the wall of which is provided with one or more ports for the passage of liquid and vapor, which receptacle is housed in the boiler.

2

In this manner no trouble is experienced from effervescence of the boiling liquid inside the boiler and, moreover, said receptacle is particularly useful for holding as constant as possible the convection losses incurred on placing the control member in the vapor above the level inside the boiler.

In order that the invention may be readily carried into effect, it will now be described in detail with reference to the accompanying drawing, in which—

10 FIG. 1 shows diagrammatically one form of a gas-fractionating column according to the invention in longitudinal section.

FIG. 2 shows diagrammatically one form of the control member with its surroundings, which constitutes the 15 main element of the invention,

FIG. 3 is an elevation of a further form of the control member.

The gas-fractionating column shown in the drawing essentially comprises an elongated cylinder 1, the lower 20 end of which is connected to a boiler 2. This boiler has an exhaust conduit 32 for oxygen. The assembly is surrounded by heat-insulating material 3.

The gas to be fractionated, for example air, is supplied at 4 and enters, through the duct 5, the chamber 6 25 below the boiler 2. The duct 5 comprises devices, not further referred to, for separating water, carbon dioxide and acetylene from the air. The air flows past fins 7 of the boiler 2 and rises through the space 8 along the boiler 2 into the column 20. At 9 the air enters the separating 30 chamber proper of the column. In the present form, this chamber has two parts 10 and 11 which are filled with Raschig-rings or other material for packing the column.

The space 12 above the chamber 10 is connected through the duct 13 with the nipple 14. To this nipple 35 14 there may, for example, be connected a gas refrigerator as a thermal sink.

Through the duct 15 of the nipple 14, vapor of the low-boiling fraction (nitrogen in the case of air) is drawn off. This vapor is condensed by the heat sink and the condensate runs through the duct 15 back to the column and collects at the lower end of the duct 13, whence the condensate is passed upwards to the space 12 through a vapor-bubble pump 16.

Liquid distributors or receivers are designated by 17 and 18.

45 The duct 19 opens into the annular duct 13 for carrying off the product, that is pure liquid nitrogen in the case of fractionating air.

To the lower end of the pump tube 16 there is connected (see also FIG. 2) a heat-conductive strip 23 passing through the insulation 3 to a location 24 which may, for example, be connected to a conduit for water of ambient temperature.

50 At 25 the strip 23 is connected to a control member 26 having a substantially conical lower part 26a adjoining a cylindrical part 26b which merges into a part 26c, which tapers to the lead-through 25 through the boiler wall 27. A lead-through member consisting of heat-insulating material is designated by 28.

60 The control member 26 extends into the boiler, where it is surrounded by a receptacle 31 provided with ports 29, 30.

When the level in the boiler is low, for example the line 2-a in FIG. 2, much heat is supplied through the strip 23 to the vapor-bubble pump 16 so that a large quantity of 65 condensate is refluxed to the column. In this case, the temperature at 25 is, for example, 150° K. in the case of fractionating air, and the heat flow through the strip 23 from point 23a to the vapor-bubble pump 16 is considerable. The level will then rise inside the boiler.

At the level b-b in the boiler, the temperature at 25 is reduced to, say, 110° K. (the temperature of the coil liquid in the boiler, that is liquid oxygen in the case of

fractionating air, is 86° K. for oxygen). In this case less heat is supplied to pump 16.

At the level *c*—*c*, the temperature at 25 is further reduced to say, 90° K. The supply of the pump 16 further decreases and the level no longer rises in the boiler.

The varying thermal resistance of the control member 26 should be properly chosen.

It has been found that a substantially conical pin yields excellent results.

Alternatively, other forms are possible. Thus, for example, FIG. 3 shows a block 35 of conductive material having secured to it a number of strips 33 having different lengths. The thermal resistance of this block forms a level *a*—*a* to the area 34, where the block 35 passes through the wall of the boiler, is also variable at different levels.

What is claimed is:

1. A gas fractionating apparatus co-acting with a thermal sink comprising an insulated column having a boiler in the bottom thereof, said thermal sink being adapted to carry off vapor from said column and condense the same, a distributor for condensate returning to said column, conduit means in the insulated portion of said column connecting said thermal sink to the upper part of said column, said conduit means communicating with said distributor for the condensate returning to said column and a vapor lift pump in the insulated portion of said column operatively connected to said distributor, a heat conductive member in said column having an external source of applied heat and being in heat conducting relationship with said vapor lift pump, said returning condensate being conducted to the lower end of said vapor lift pump whereby said condensate is caused to rise therein due to said source of applied heat until it spills into said column, a portion of said heat conductive member being adapted to assume a temperature higher than that of said condensate, a control element in said boiler for automatically controlling the level of liquid in the boiler being reduced in cross-section at the end closest to the bottom of said boiler, said heat conductive member being operatively connected to said element, said control element being in heat exchanging contact with the liquid in said boiler, and said reduced end of the control element being so shaped and proportioned that the thermal resistance of the element varies at different distances between the junction of the element with the heat conductive member and the liquid level inside said boiler.

2. A gas fractionating apparatus as claimed in claim 1 wherein the thermal resistance of said control element is such as to prevent oscillation during control.

3. A gas fractionating apparatus co-acting with a thermal sink comprising an insulated column having a boiler in the bottom thereof, said thermal sink being adapted to carry off vapor from said column and condense the same, a distributor for condensate returning to said column, conduit means in the insulated portion of said column connecting said thermal sink to the upper part of said column, said conduit means communicating with said distributor for the condensate returning to said column and a vapor lift pump in the insulated portion of said column operatively connected to said distributor, a heat conductive member in said column having an external source of applied heat and being in heat conducting relationship with said vapor lift pump, said returning condensate being conducted to the lower end of said vapor lift pump whereby said condensate is caused to rise therein due to said source of applied heat until it spills into said column, a portion of said heat conductive member being adapted to assume a temperature higher than that of said condensate, a control element in said boiler shaped as a conical pin for controlling the contact of said member with the liquid in said boiler, an enclosure for said control element having apertures therein, said control element being in heat exchanging contact with the liquid in said boiler, and said conical control element being so shaped

and proportioned that the thermal resistance of the element varies at different distances between the junction of the element with the heat conductive member and the liquid level inside the boiler.

4. A gas fractionating apparatus co-acting with a thermal sink comprising an insulated column having a boiler in the bottom thereof, said thermal sink being adapted to carry off vapor from said column and condense the same, a distributor for condensate returning to the column, conduit means in the insulated portion of said column connecting said thermal sink to the upper part of said column, said conduit means communicating with said distributor for the condensate returning to said column and a vapor lift pump in the insulated portion of said column operatively connected to said distributor, a heat conductive member in said column having an external source of applied heat and being in heat conducting relationship with said vapor lift pump, said returning condensate being conducted to the lower end of said vapor lift pump whereby said condensate is caused to rise therein due to said source of applied heat until it spills into said column, a portion of said heat conductive member being adapted to assume a temperature higher than that of said condensate, a control element in said boiler shaped as a conical pin for controlling the contact of said member with the liquid in said boiler, an enclosure for said control element having apertures therein, said control element being in heat exchanging contact with the liquid in said boiler, and said conical control element being so shaped and proportioned that the thermal resistance of the element varies at different distances between the junction of the element with the heat conductive member and the liquid level inside said boiler.

5. A gas fractionating apparatus co-acting with a thermal sink comprising an insulated column having a boiler in the bottom thereof, said thermal sink being adapted to carry off vapor from said column and condense the same, a distributor for condensate returning to the column, conduit means in the insulated portion of said column connecting said thermal sink to the upper part of said column, said conduit means communicating with said distributor for the condensate returning to said column and a vapor lift pump in the insulated portion of said column operatively connected to said distributor, a heat conductive member in said column having an external source of applied heat and being in heat conducting relationship with said vapor lift pump, said returning condensate being conducted to the lower end of said vapor lift pump whereby said condensate is caused to rise therein due to said source of applied heat until it spills into said column, a portion of said heat conductive member being adapted to assume a temperature higher than that of said condensate, a control element in said apparatus for controlling the contact of said member with the liquid in said boiler, an enclosure for said control element having at least one opening for the passage of liquid therethrough, said enclosure being located in said boiler, said control element having a reduced cross-section at the end thereof closest to the bottom of the boiler being in heat exchanging contact with the liquid in said boiler, and the reduced end of said control element being so shaped and proportioned that the thermal resistance of the element varies at different distances between the junction of the element with the heat conductive member and the liquid level inside said boiler.

6. A gas fractionating apparatus co-acting with a thermal sink comprising an insulated column having a boiler in the bottom thereof, said thermal sink being adapted to carry off vapor from said column and condense the same, a distributor for condensate returning to the column, conduit means in the insulated portion of said col-

umn connecting said thermal sink to the upper part of said column, said conduit means communicating with said distributor for the condensate returning to said column and a vapor lift pump in the insulated portion of said column operatively connected to said distributor, a heat conductive member in said column having an external source of applied heat and being in heat conducting relationship with said vapor lift pump, said returning condensate being conducted to the lower end of said vapor lift pump whereby said condensate is caused to 10 rise therein due to said source of applied heat until it spills into said column, a portion of said heat conductive member being adapted to assume a temperature higher than that of said condensate, a control element in said apparatus being a block of conductive material having 15 heat conducting strips of various lengths extending in the direction of the liquid in the liquid boiler, an enclosure for said control element having apertures therein,

said control element being in heat exchanging contact with the liquid in said boiler, and said heating conducting strips of said control element being so shaped and proportioned that the thermal resistance of the element varies at different distances between the junction of the element with the heat conductive member and the liquid level inside said boiler.
